CLAIM

The ornamental design for a connector and port arrangement with cylindrical segment tube retainers, as shown and described.

DESCRIPTION

FIG. 1 is a perspective view of a port arrangement and tube retainers of a connector, with the remainder of the connector being shown in phantom;

FIG. 2 is front elevational view thereof, the rear forming no part of the port arrangement and tube retainer design;

FIG. 3 is a right side elevational view thereof, the left side elevational view being a mirror image thereof;

FIG. 4 is a top plan view thereof; and,

FIG. 5 is a bottom plan view thereof.

The phantom lines in the drawings indicate environmental structure which forms no part of the claimed design.
